UNITED STATES PATENT OFFICE.

ISRAEL J. EVIN, OF ALTOONA, PENNSYLVANIA.

SOLE-CHANNELING MACHINE.

1,200,329.

Specification of Letters Patent.

Patented Oct. 3, 1916.

Application filed April 7, 1916. Serial No. 89,714.

To all whom it may concern:

Be it known that I, ISRAEL J. EVIN, a citizen of the United States, residing at Altoona city, in the county of Blair and State of Pennsylvania, have invented certain new and useful Improvements in Sole-Channeling Machines; and I do declare the following to be a full, clear, and exact description of the invention, such as will enable others skilled in the art to which it appertains to make and use the same.

My invention is a machine for channeling shoe soles, the object thereof being to provide a device of this class which although being simple and inexpensive, will be highly efficient and durable and will readily channel the soles of shoes while they are attached to the upper.

With this general object in view, the invention resides in certain novel features of construction and in unique arrangements of parts to be hereinafter fully described and claimed, the descriptive matter being supplemented by the accompanying drawings which constitute a part of this application and in which:

Figure 1 is a side elevation partly in section of a machine constructed in accordance with my invention; Fig. 2 is a top plan view thereof; Fig. 3 is a vertical transverse section taken on the plane indicated by the line 3—3 of Fig. 1; Fig. 4 is an end elevation partly in section; Fig. 5 is a fragmentary rear elevation with parts in section; Fig. 6 is a detail transverse section taken on the plane indicated by the line 6—6 of Fig. 5; Fig. 7 is a perspective view of the bracket which controls the depth of the channel cut by the channeling knife; Fig. 8 is a disassembled perspective view of the adjusting means for the pressing lever; and Fig. 9 is a detail front elevation showing the machine in operation upon a shoe sole.

In specifically describing the construction shown in the drawings above briefly described, similar characters will be placed on corresponding parts throughout the several views and reference will be herein made to the numerous elements by their respective indices. To this end, the numeral 1 designates a vertical standard preferably of hollow construction and having an annular base flange 2 by means of which it may be attached to a shoemaker's bench. Rising from the upper end of the standard 1 are two

bearing brackets 3 and 4, the bracket 3 having a vertical extension 5 while a pair of ears 6 rise from the bearing 4. Also extending vertically from a portion of the bearing 3 between the extension 5 and the ears 6 is a post 7 whose upper end is forked at 8 and constitutes a horizontal guide, one side of the fork having a vertical slot 9 for a purpose to appear.

An upright stub shaft 10 is secured by a set screw or the like 11 in the extension 5 of bearing 3, a horizontally disposed feed wheel 12 being mounted rotatably on said shaft and held in operative position thereon by means of a screw 13 whose head is received in a cavity 14 in said wheel, said screw being threaded into the upper end of the stub shaft 10. A beveled pinion 15 is formed integrally with the lower side of the feed wheel 12, said pinion being in mesh with a beveled gear 16 secured on one end of a longitudinally disposed operating shaft 17 which is rotatably mounted in the bearings 3 and 4. Any preferred means may be provided for driving the shaft 17, but a fly wheel 18 is preferably secured to one end thereof, said wheel having a peripheral groove 19 for the reception of a driven belt if the machine is to be operated by power, but having a crank 20 whereby it may be actuated by hand.

The upper side of the feed wheel 12 at the edge thereof is provided with teeth 21 adapted to engage a shoe sole when the latter is being operated upon by the machine as shown in Fig. 9, said upper side of the wheel 12 also having an upstanding annular shoulder 22 which is adapted to engage the edge of the shoe sole to effectively guide the latter.

A pressing lever 23 passes slidably through the fork 8 and is provided at one end with a horizontal slot 24, this end of the lever being received between the ears 6 in which position it is retained by a pin 25 passing through said ears and through said slot. The other end of the lever 23 is disposed above the feed wheel 12 and carries a channeling knife 26 and a bracket 27, which latter controls the depth of the cut made by the knife. The lever 23 is normally depressed by the tension of a coiled spring 28 which forces downwardly upon a stop 29 on the lower end of an upright rod 30, the upper end of said rod being pivoted at 31

- to the aforesaid lever. As shown most clearly in Fig. 3, the lower end of the rod 30 and the spring 28 are received in the hollow standard 1.
- 5 When it is necessary to raise the free end of the lever 23 to permit the insertion and removal of shoe soles, a hand lever 32 will be depressed, said lever being fulcrumed between its ends on the shaft 17 between the 10 bearings 3 and 4. One end of the lever 32 is bifurcated at 33 for the reception of the rod 31, the furcations of this end of the lever engaging the under side of a collar 34 which is secured to the rod 30 by a set screw 15 35 or other suitable means. By mounting the lever 32 on the shaft 17 it will be obvious that other fulcruming means for said lever is eliminated and thus the machine is simplified.
- 20 At times it becomes necessary to shift the lever 23 horizontally, in order to dispose the knife 26 for channeling at different distances from the edge of the shoe sole, this being accomplished by the construction now 25 to be described. A rectangular block 36 is mounted slidably but non-rotatably in the slot 9 of fork 8, said block having formed horizontally therethrough a circular bore 37. The bore 37 receives therein a cylindrical 30 block 38 through which an eccentric bore 39 extends. A clamping screw 40 passes through bore 39 and is threaded into the lever 23, the outer end of said screw being squared at 41 for the reception of a key 42 (see dotted lines in Fig. 3) and said end of this screw 40 has formed thereon an outstanding flange 43 which is adapted to be forced into frictional engagement with the outer end of the cylindrical block 38 when 40 the screw is tightened, thereby normally holding said block against rotation. The block 38 however, is formed with radial sockets 44 opening through its periphery as shown most clearly in Figs. 3 and 8, said 45 sockets being adapted for engagement by a spanner wrench or the like when screw 40 is loosened. It will thus be evident that the block 38 constitutes an eccentric which when properly turned will adjust the screw 40 horizontally, the lever 23 moving with said screw. During this operation, said lever 23 will neither be raised nor lowered due to the fact that the block 36 will slide vertically 50 within the slot 9. As lever 23 moves horizontally, the rod 30 may yield but the opening 45 in the standard 1 through which said rod passes is preferably made sufficiently large to allow said rod to cant the necessary amount.
- 55 The knife 26 above referred to may be of any suitable construction but is preferably shaped approximately as shown in Fig. 5, said knife having an attaching plate 46 which is secured by set screws 47 to a flange 60 48 formed integrally with and depending from the lever 23. As heretofore stated, the distance which the knife 26 penetrates the sole of the shoe is regulated by the bracket 27 which latter is of rather unique construction for this purpose. The bracket in question is formed of a single piece of metal preferably though not necessarily cast, said bracket being arched as shown clearly in Figs. 4, 6 and 7 with its legs 49 and 50 disposed in sliding contact with the front and 70 rear sides of the free end of the lever 23, the leg 50 being greater in length than 49 and extending a considerable distance below said end of the lever. The lower end of said arm 50 is bifurcated, the furcations 51 75 thereof receiving therebetween a sole engaging shoe 52 which is preferably in the form of a roller as shown. The upper end or top plate 53 of bracket 27 has formed therein a slot 54 which receives the intermediate portion of an upright adjusting screw 55 which is threaded into the free end of the lever 23, said screw having collars 56 above and below said plate 53 whereby as said screw is turned by the key 42 or by other suitable means, the entire bracket 27 will be adjusted vertically to raise or lower the shoe 52, thereby allowing the knife 26 to penetrate a greater or less amount into the shoe sole, said shoe 52 engaging the shoe sole as shown in Fig. 9. 80 For locking the bracket 27 in its vertically adjusted position, the leg 50 thereof will preferably be provided with an opening 57 through which a clamping screw 58 passes loosely, said screw having a squared outer 85 end equipped with a flange 59 to engage the leg 50 when said screw is tightened, the inner end of the latter being threaded into the lever 23 as shown in Fig. 4.
- 85 The operation of the improved machine is 105 as follows:—The shoe sole whether independent of or attached to an upper is disposed in the machine as shown in Fig. 9, this being allowed by first raising the lever 23 through the instrumentality of the hand lever 32. Said lever 23 is now adjusted horizontally to position the knife 26 the desired distance from the edge of the sole and the bracket 27 is likewise adjusted to allow said knife to penetrate the sole the necessary amount. These adjustments having 110 been made, the shaft 17 will be rotated with the result that the gear and pinion 16 and 15 respectively will rotate the feed wheel 12, the latter now advancing the sole of the shoe 115 against the knife which cuts therein a channel to receive the usual stitches by means of which the sole is secured to the projecting welt of the shoe. During the channeling operation, if the welt be sufficiently wide, the 120 edge of the sole will engage the shoulder 22 which will serve as a gage to cause the channel to be spaced equi-distantly from said edge throughout its length. However, when 125 channeling more finely constructed shoes, the 130

edge of the wheel 12 will engage the upper thereof to accomplish the result just set forth.

From the foregoing, taken in connection with the accompanying drawing, the construction, manner of operation and advantages of the improved machine will be readily understood without requiring a more extended explanation. In conclusion, however, I will state that although I have shown and described certain details of construction for accomplishing probably the best results, numerous changes may be made within the scope of the invention as claimed without sacrificing the main advantages thereof.

I claim:

1. In a sole channeling machine, the combination of a horizontally disposed feed wheel upon whose upper side at one edge thereof a shoe sole is adapted to rest, said side of the wheel having an upstanding annular shoulder concentric with its periphery to engage the edge of the sole and guide the latter, means for driving said feed wheel, and a sole channeling knife above the aforesaid edge of said wheel.

2. In a sole channeling machine, the combination of a support, a feed wheel mounted thereon, means for driving said wheel, a vertically movable pressing lever mounted on said support and having one end disposed above said feed wheel, an arched bracket straddling said end of the lever and mounted for vertical adjustment thereon, the lower end of one leg of said bracket being bifurcated, a channeling knife depending from said end of the lever, and a sole engaging roller mounted between the ramifications of the bifurcated leg of said bracket, said roller serving to regulate the depth of cut made by the knife.

3. In a sole channeling machine the combination of a support, a feed wheel mounted thereon, means for driving said wheel, a pressing lever mounted on said support and having one end disposed above said feed wheel, a channeling knife carried by said end, an arched bracket straddling this end of the lever and having its legs disposed in sliding contact with opposed sides thereof, one of said legs having an opening, a clamping screw passing through said opening into the lever, an adjusting screw swiveled in the upper end of the bracket and threaded in said lever, the lower end of one of said legs

of the bracket being bifurcated, and a sole engaging roller mounted between the ramifications of said leg.

4. In a sole channeling machine, the combination of a support including a horizontal guide having in one side a slot, a pressing lever passing slidably through said guide and having on one end a channeling knife, a feed wheel below said end of the lever, means for driving said wheel, a block slideable vertically but non-rotatably in the slot of the guide and having a circular bore, a cylindrical block rotatably mounted in said bore and itself having an eccentric bore, and a clamping screw passing through said eccentric bore and threaded into the lever.

5. In a shoe channeling machine, the combination of a support, a feed wheel mounted thereon, means for driving said feed wheel including a horizontal shaft, a vertically movable pressing lever having at one end a channeling knife disposed above said feed wheel, an upright rod pivoted to and depending from said lever in close proximity to the aforesaid shaft, spring means in conjunction with said rod for normally exerting a downward stress thereon, and a hand lever fulcrumed on the aforesaid shaft for raising said rod at will against the tension of said spring means.

6. In a shoe channeling machine, the combination of a support, a feed wheel mounted thereon, means for driving said feed wheel including a horizontal shaft, a vertically movable pressing lever having at one end a channeling knife disposed above said feed wheel, an upright rod pivoted to and depending from said lever in close proximity to the aforesaid shaft, spring means in conjunction with said rod for normally exerting a downward stress thereon, a collar secured on said rod, and a hand lever fulcrumed on the aforesaid shaft, said lever having a bifurcated end straddling said rod and engaging the lower side of the collar thereon, whereby said lever may operate to raise said rod against the tension of the aforesaid spring means.

In testimony whereof I have hereunto set my hand in presence of two subscribing witnesses.
